(57) **CLAIM**

The ornamental design for a tire tread, as shown and described.

DESCRIPTION

FIG. 1 is a perspective view of a tire tread showing my new design, it being understood that the pattern repeats uniformly throughout the circumference of the tread;

FIG. 2 is a front elevational view thereof;

FIG. 3 is a right side elevational view thereof; the opposite side elevational view being a mirror image thereof;

FIG. 4 is an enlarged fragmentary front elevational view thereof;

FIG. 5 is a perspective view of an alternate embodiment of a tire tread showing my new design;

FIG. 6 is a front elevational view of the alternate embodiment;

FIG. 7 is a right side elevational view of the alternate embodiment; the opposite side elevational view being a mirror image thereof; and,

FIG. 8 is an enlarged fragmentary front elevational view of the alternate embodiment.

In the drawings, the broken lines defining the sidewall, inner bead and the peripheral boundary between the tire tread and the sidewall are for illustrative purposes only and form no part of the claimed design.
